VALVE MECHANISM

John J. Kupka, New Brunswick, N. J., and Gordon T. Wilson, Buffalo, N. Y.

Application November 12, 1936, Serial No. 110,516

4 Claims. (Cl. 121—163)

The present invention relates to locomotive steam engines and more particularly to the valve operating mechanism for same, and has for its primary object the provision of an improved 5 valve mechanism by which to increase the operating efficiency of the engine.

In the conventional type of locomotive now in common use the steam engine for same includes a reciprocating slide or piston valve controlling 10 the inlet and exhaust ports of the engine, the valve having a total lineal travel considerably in excess of the actual travel required to move the valve relative to the ports, the added travel being required to provide a portion of the cycle 15 in which the valve comes to rest and begins its reverse action movement. Such operation is required in order that the valve, in its operation relative to the steam ports, may be moved at a rate of travel commensurate with the time allotted for the entrance and exhaust of the steam 20 to or from the power cylinder.

In view of the above a more specific object is to provide, in a locomotive valve mechanism, means for accelerating and decelerating the reciprocating motion of the engine's valve so as to 25 permit the entrance and exhaust of the pressure steam at the critical instants required to afford a high degree of efficiency in power output.

Another object is to provide an accelerator 30 valve mechanism for locomotive steam engines and the like which in operation functions to materially reduce the total travel of the engine valve, effecting thereby an appreciable reduction in the size and wear of the moving parts 35 particularly the valve and housing for same, consequently providing a valve operating mechanism capable of extended uninterrupted service by partially obviating the necessity for the usual frequent maintenance and repair.

A further object is to provide an accelerator 40 mechanism cooperating with the valve for steam engines adapted to be incorporated in the conventional type of valve operating means now in common use in steam locomotives and particularly adapted to be included with the usual cylinder 45 and valve chamber arrangement employed.

The invention will be fully and comprehensively understood from a consideration of the following detailed description when read in connection with the accompanying drawings which 50 form part of the application.

In the drawings:

Fig. 1 is a side elevational view of the engine mechanism of a typical locomotive incorporating 55 therein the valve accelerator mechanism, por-

tions of the apparatus being shown in central section.

Fig. 2 is an enlarged detail view of the valve accelerator mechanism, being a longitudinal sectional view thru same.

Fig. 3 is a transverse section taken on line 3—3 of Fig. 2.

Fig. 4 is a horizontal section taken on line 4—4 of Fig. 3.

Fig. 5 is a fragmentary perspective view of the 10 main elements of the accelerator mechanism; and

Figs. 6 and 7 are diagrammatic views of the valve accelerator mechanism shown in two positions assumed during the cycle of operation. 15

By reference to Fig. 1 it will be apparent that the engine valve accelerator mechanism is illustrated as being adapted to the conventional type of locomotive steam engine comprising a power cylinder 8 in which is slidably carried a drive 20 piston 9 having a piston rod 10 extending therefrom. The piston rod 10 at its opposite end is secured to a cross head 11 slidably carried for reciprocating movement on guide bars 12, the latter being fixed to a guide bar yoke or frame 25 13. To the cross head 11 is flexibly connected a main drive rod 14, the opposite end of which is connected to a crank pin carried on the driving wheel 15 of the locomotive for driving the same. The power cylinder 8 and its associated 30 piston 9 are of the conventional double action type, being adapted to impart power to the driving wheels during either direction of travel. Steam from the locomotive boiler is introduced at high pressure to the engine thru a supply pipe 35 16, the discharge of the steam to the cylinder 8 being controlled by a piston valve 17. In view of the double action of the power cylinder 8 the valve 17 comprises two spools 18 functioning, during their sliding action, to open and close 40 entrance ports 19 communicating with the respective ends of the power cylinder 8. The action of either spool 18 of the valve 17 relative to the respective entrance ports 19 serves to first admit steam into the power cylinder by being disposed to one side of the port 19, and thereafter to permit the exhaust of the steam 45 thru the respective exhaust ports 20 by being disposed toward the opposite side of the entrance port 19 after a suitable period for the expansion of the steam in imparting power to the piston 9.

In the conventional type of locomotive engine a combination lever 21 is provided for actuation of the valve 17, the lever 21 being flexibly cou- 55

plied at one end to the cross head 11 by a union link 22. Actuation of the valve 17, in the conventional type of valve mechanism in common use, is effected thru the combination lever 21 to 5 a valve stem 23 extending from the valve 17, the valve stem 23 being, in this instance, flexibly connected to the lever 21. The combination lever 21 in actuating the valve 17, is fulcrumed at 24 on an end of a radius bar 25, the opposite 10 site end of which is flexibly secured to a block 26. The block 26 is adjustably retained in a rocker link 27, the position of the block 26 therein being moved to the desired setting by operation of a lifting link 28 connected thereto, the 15 lifting link being actuated by an arm 29 carried on a reversing shaft 30 from which extends a reversing arm 31.

The rocker link 27 is swingably carried on the frame 13 and is actuated in a rocking motion by 20 an eccentric rod 32 flexibly coupled therewith and actuated at its free end by association with an eccentric pin on the driving wheel 15. By adjusting the block 26 to various positions within the rocker link 27 the power of the engine is 25 varied, the adjustment being effected by operation of the lever 31. The block 26 being positioned toward one end of the rocker link 27 serves to actuate the locomotive in the forward direction, the block 26 being positioned toward the 30 opposite end of the rocker link 27 serving to reverse the direction of the locomotive.

The association and cooperation of the various elements comprising the steam engine particularly the connection of the combination lever 21 to 35 the valve stem 23, thus far described, being of the conventional type, are well known to those skilled in the art. It is to be noted, however, that the valve 17 being so operated must be reciprocated an appreciable distance during a 40 cycle of operation of the engine so that each of the spools 18 thereof are moved to and from registry with its entrance port 19 at a travel commensurate with the required performance of the engine. That is, the spool 18 in moving to open 45 the port 19 must travel at a speed so that the port 19 is opened or closed in a minimum of time. This prerequisite necessitates an excessive travel of the valve 17 so that ample time is afforded for reversing the travel of same, which is accomplished by moving the spools 18 appreciably beyond their normal path of travel until the reverse 50 action is attained. To obviate this objection, specifically by reducing the required travel of the valve 17, the accelerator mechanism 34 is provided.

A detailed description of the valve accelerator mechanism 34 now follows during which attention is particularly directed to Figs. 2, 3 and 4. 55 The numeral 35 indicates an accelerator cam flexibly connected at one end to the combination lever 21, the oscillation of the latter serving to impart a reciprocating action to the cam 35. The cam 35 is slidably carried on a slide plate 36 in conjunction with a guide frame 37 fixedly secured to the frame 13. The cam 35 comprises a substantially flat intermediate area 38 terminating at each end in inclined portions 39 and 40. A rocker lever 41 of substantially T-shape 60 comprises opposed arms 42 extending from either side of the lever and a depending arm 43 flexibly coupled at its free end by a link 44 to the valve stem 23. The arms 42 are provided with rollers 45 the latter being in contact with the 65 cam surface of the accelerator cam 35. The

rocker lever 41 is mounted for rocking movement on a shaft 46 fixed to the guide frame 37.

In considering the operation of the entire valve mechanism with reference to the actuation of the valve 17 a clearer understanding of same will be had by observing the functioning of the accelerator lever 41 in cooperation with the combination lever 21. Movement of lever 21, as previously described, serves to actuate the accelerator cam 35 in a reciprocating action, the extent of 10 the travel being variable by adjustment of the block 26 in the rocker link 27. The accelerator mechanism 34 serves primarily to accelerate the travel of the valve 17 during opening of same and correspondingly to accelerate the travel of same 15 during closing relative to the respective ports 19. By reference to Fig. 1 it may be assumed that the spool 18 is being moved to open the port 19, the opening being accomplished in a short interval of time. At the start of operation, the rocker lever 20 41 is disposed in central position having both of its rollers 45 in contact with the respective inclines 39 and 40. As the accelerator cam 35 is slid in one direction the rocker lever 41 immediately assumes an angular position as illustrated 25 in Fig. 6 so that the spool 18 is rapidly moved beyond the port 19 to admit steam therethrough. The cam 35 continues to slide as the pressure steam is admitted in the power cylinder 8 during 30 which the cam is disposed substantially as shown in Fig. 7. By comparison with the showing in Fig. 6, it will be noted that the rocker lever 41 has maintained its angular position from which it will be apparent that the valve 17 is held in full open position during this cycle. Upon sliding the cam 35 in the opposite direction the reverse 35 action takes place and the valve 17 is rapidly moved to exhaust position by operation of the accelerator mechanism 34. From this it will be seen that the accelerated travel of the valve 17 40 during opening and closing of the port 19 permits a substantial decrease in the total travel of the valve resulting in a more efficient operation of the engine by minimizing the time required to open and close the controlling valve. In that 45 the valve of the improved mechanism may accomplish its function during a shorter travel the power required to overcome the inertia is minimized thereby effecting a reduction in the wear of the associated mechanism. 50

The co-relation of the accelerator mechanism 34 to the combination lever 21 as illustrated in Fig. 1 permits of arranging the valve 17 in close association with the power cylinder 8 without reducing the effective stroke of the valve, in that 55 the accelerator cam 35 is coupled to the combination lever 21 beyond the connection of the radius bar 25 thereto thus reducing to a minimum the objectionable clearance space between the power 60 cylinder and the piston valve. The invention also makes it possible to increase the effect of the rocker link 27 on the cam 40 by arranging the connection to the rocker link 27 thru the radius bar 25 so as to be intermediate the ends of the 65 combination lever 21.

In the preferred embodiment of the invention illustrated in the drawings the conventional type of valve actuating mechanism is employed to operate the slide cam 35 of the accelerator mechanism 34, in that same permits of incorporating the invention with the locomotive mechanisms now in common use. It will, however, be apparent that the invention may be adapted for use in combination with other types of actuating mech- 70 75

anisms without departing from the spirit of the invention, the mechanism including suitable means for controlling the power of the engine by synchronous movement of the fulcrum 24 of the combination lever 21 so as to vary the stroke of the cam 35.

It is to be understood that this improvement is capable of extended application and is not confined to the exact showing of the drawings nor to the precise construction described and, therefore, such changes and modifications may be made therein as do not affect the spirit of the invention nor exceed the scope thereof as expressed in the appended claims.

15. What is claimed as new is:

1. Valve operating mechanism for pressure actuated engines including a power cylinder and a piston slidable therein, comprising in combination therewith a slide valve for control of pressure to or from said piston, a rockable lever fulcrumed on said engine and comprising opposed arms extending from said fulcrum and a valve arm depending from said lever and connected to said valve for actuating same, a slideable flat cam having 20 synclined portions for engagement with said opposed arms, and means operable by movement of said piston for reciprocating said cam, and comprising a combination lever flexibly connected respectively to said piston and said cam.

30. 2. In a locomotive engine including a steam actuated power cylinder having a piston slidable therein and a valve for control of steam to or from said cylinder, valve operating mechanism comprising a combination lever connected to said piston, a rocker link oscillated by travel of said locomotive, a block adjustably carried in said rocker link, a radius bar carried on said block and forming a fulcrum for said combination lever, a rockable lever fulcrumed on said engine, a slideable flat cam actuatable by said combination lever for oscillating said rocking lever whereby to slide said valve at varying rates of travel in control of steam to or from said power cylinder.

40. 3. In a pressure actuated engine having a power cylinder and power piston slidably mounted therein, a slide valve controlling the inlet and outlet ports of said power cylinder, said

valve including a cylinder having outlet and inlet ports formed in the walls thereof and a valve element slidable in said cylinder and registerable with said ports whereby they can be opened or closed by varying the position of said element, 5 the mechanism for operating said slide valve comprising a flat sliding member having a synclined cam face formed on one surface thereof, means for imparting reciprocating movement to said sliding member comprising a lever system 10 associated with said power piston and said member, and a T-shaped rider element engaging with the cam surface on said sliding member and reciprocably actuating the valve element in said slide valve.

15. 4. In a pressure actuated engine having a power cylinder and power piston slidably mounted therein, a slide valve controlling the inlet and outlet ports of said power cylinder, said valve including a cylinder having inlet and outlet 20 ports formed in the walls thereof and a valve element slidable in said cylinder and registerable with said ports whereby they can be opened or closed by varying the position of said element, the mechanism for operating said slide valve 25 comprising a flat sliding member having a synclined cam face formed on one surface thereof, means for imparting reciprocating movement to said sliding member comprising a lever system associated with said power piston and said member, whereby the movement of said member is directly and arithmetically proportional to the movement of said power piston during the entire cycle of oscillation of the latter, and a T-shaped rider element engaging with the cam surface on 30 said sliding member and reciprocably actuating the valve element in said slide valve, the movement of said valve element during actuation of the power piston being characterized in that the movement of the valve element is always other 35 than directly and authentically proportional to the movement of the power piston, and that during a portion of the cycle of movement of the power piston, the valve element is maintained substantially stationary.
